Filed Mar. 22, 1965, Ser. No. 84,380

Term of patent 3½ years

(Cl. D91—3)

FIG. 1.

FIG. 2.

FIG. 3.

FIG. 4.

FIGURE 1 is an elevational view of a gate valve, showing our new design.

FIGURE 2 is a fragmentary perspective view illustrating a portion of the gate valve of FIGURE 1.

FIGURE 3 is a bottom view of the gate valve of FIGURE 1.

FIGURE 4 is a right side elevation of the gate valve of FIGURE 1.

The left side elevational view of the valve is substantially a mirror image of the view illustrated in FIGURE 4.

The opposite end and side views of the valve are substantial duplicates of the end and side views illustrated in FIGURES 1 and 4, respectively.

The dominant features of the design illustrated in the various figures reside only in the features shown in full lines.

We claim:

The ornamental design for a gate valve, as shown and described.
